R. W. BOOTH

PROCESS FOR MAKING CORK DISKS

Filed Jan. 17, 1923

RALPH W. BOOTH

INVENTOR

BY *Julian M. Vitale*

ATTORNEY

UNITED STATES PATENT OFFICE.

RALPH W. BOOTH, OF BROOKLYN, NEW YORK.

PROCESS OF MAKING CORK DISKS.

Application filed January 17, 1923. Serial No. 613,275.

To all whom it may concern:

Be it known that I, RALPH W. BOOTH, a citizen of the United States, and residing at 1198 Pacific Street, Brooklyn, New York, ⁵ have invented a new and useful Improvement in Processes for Making Cork Disks, of which the following is a specification.

This invention relates to the manufacturing of cork disks for closures of bottles and ¹⁰ has for its main object to provide means whereby the rotating knives which are mainly used for cutting such disks will be automatically cooled and lubricated, while the operation is going on.

¹⁵ Another object of the invention is to prevent the tearing of the cork material which usually accompanies the present methods of cutting such disks.

Still another object of this invention is ²⁰ to provide means to lubricate the disks, the metal crowns and the assembled crown corks in the further operations of their preparation and to aid in the sealing of the bottles.

Incidentally my invention will help ²⁵ through all the mentioned operations in increasing the capacity and efficiency of the different machines and devices used to perform said operations.

My invention mainly resides in covering ³⁰ the rods from which said disks are cut with a thin coat of paraffin, ceresin or similar oily, fatty or wax like materials, before the cutting operation is started.

In order to obtain the different advantages and objects described hereinbefore, I ³⁵ take the rod of cork and dip it in a tank containing molten paraffin, ceresin or similar materials, or coat said rod with a thin layer of such materials by any other suitable means. After the rod is cooled and ⁴⁰ said coating solidified, it is ready to be fed into any of the devices or machines used to cut the cork disks to be used for closures of bottles.

⁴⁵ One of the drawbacks and sources of trouble experienced with such machines and devices is the heating of the knives or other cutting tools. Such machines usually operate with rotating knives and in the rapid succession of operations, the friction of said knives on the cork material will heat both of them to a considerable degree. This heating has harmful effects not only on the knives themselves but also on the disks cut, many

of which are torn and uneven. They also ⁵⁵ may deteriorate in many other respects on account of the heating. My cork rod, having been previously coated with said paraffin, ceresin or other materials, will automatically lubricate the knives by the melting ⁶⁰ of said coating during the operation and thereby not only facilitate the cutting operation but also prevent an excessive rise of temperature of said knives or of the cork. My experience with such operations also ⁶⁵ shows that the molten wax-like material will ultimately cover not only the cylindrical outside surfaces of the disks but will flow over the two perpendicular finishing surfaces of the same to a depth of about a quarter of an inch from the circumferences of the same.

The cork disks cut by this method will ⁷⁵ show a smooth surface and uniform dimensions, and will have considerably less number of torn and uneven specimens than those produced with the present methods. It also has been my experience that such disks will be easier to handle in the automatic machines and devices which are used for preparing and assembling the crown corks. The machine which puts the cork into the crown will have an increased capacity of about ⁸⁰ 20% to 25%. The reason for such an increase in capacity and for the generally improved facility in handling and running the machines is in the lubrication of the cork disks. Also the metal crowns themselves passing through the machine will be ⁸⁵ lubricated through coming in contact with the lubricated cork disks. The disks thus prepared are also easier to be pressed into the crown in case their dimensions are varying, and, finally, the closure of the bottles will be tighter on account of the solidified ⁹⁰ waxy or oily coating of said crowns and corks.

I also want to remark that my process for preparing the cork rods is also an aid in keeping off the knives particles of glue ¹⁰⁰ used in the composite cork rods, which heretofore have been one of the greatest troubles in the process of cutting disks of such rods and which necessitated a very frequent cleaning and resharpening of such knives. The preparation I use for my cork rods finally, also makes them rigid and stiff and greatly facilitates their handling, as ¹⁰⁵

well as the thin coating of paraffin deposited throughout the entire surface of the ready disks, make them also more resistant and stiff than when made with the present methods. This stiffening of the disks is so important that several methods have been tried heretofore, like passing such disks through a paraffin bath, but not one of such methods has proven practical. Certain composition of cork rods, otherwise very desirable and economical, are almost impossible to be cut into thin disks without previously having been prepared by my methods.

My invention can be used in any other similar cases where disks are to be cut of rods of suitable materials.

Preferably, I employ the automatic mechanism disclosed in the accompanying drawing for carrying out my improved method. In the drawing, the numeral 10 denotes an elongated base plate from which near its rear end rises a column 11, made at 12 with a forwardly directed curve so as to have a horizontal portion 13 that projects 20 forwardly above the base in substantial parallelism thereto. About midway of its height, the column 11 is constructed with a horizontally extending tubular guide 14, the greater portion of which projects forwardly 25 to come in a position between the base and horizontal portion 13. On the rearward side of the column 11, this tubular guide opens into and supports a vertically extending paraffin container 15, made with a hopper-shaped top end 16 to which at 17 is hinged a cap or closure 18. In alignment 30 with the bore 19 of the tubular guide, the container is provided with a circular aperture 20 through which the cork rod 21 is entered, passed through the paraffin in the container and then on through the tubular guide. On its interior, the container is made with the gland housings 22 and 23 which respectively surround the bore 19 and 35 aperture 20, and in these housings are disposed the ring-shaped glands 24, made of felt or other suitable material and designed to permit the advancement therethrough of the cork rod 21 while preventing any serious 40 leakage or dissipation of the paraffin when heated to a fluid or semi-fluid state.

Paraffin fragments as 25 are dropped into the hopper and in order to reduce them to a liquid or semi-liquid state for the ready coating of the cork rod, I preferably employ an electric heating device 26, disposed upon the bottom 27 of the container and having circuit wires 28 and 29 which are passed through said bottom but insulated therefrom as at 30 and 31, respectively. 45 These wires 28 and 29 are connected in circuit with any suitable source of electricity, in a manner that will be readily understood.

I now come to the mechanism for automatically cutting disk-shaped pieces from

the paraffin coated rod and to the mechanism for automatically stepping the cork rod along through the paraffin and the tubular guide prior to each cutting operation.

The horizontal portion 13 is provided with the vertical bearings or guides 32 in which are slidably mounted for vertical reciprocation the side members 33 of the frame 34 from which depends a housing 35 containing an electric motor for driving the shaft 37 which carries a circular cutting knife or disk 38. The top end of the frame 34 is made with lugs 39 for carrying a pin 40 with which the connecting rod 41 has pivotal connection at its lower end. Said connecting rod at its upper end is pivoted on an arm 42 projecting from the crank 43 attached to the shaft 44 rotatably mounted in the bearings 45 formed for the purpose on the upper ends of the forked frame 46 which is cast with the horizontal portion 13. Made fast on the shaft 44 between the bearings 45 is a pulley 47 adapted to receive a driving belt whereby to be driven from any suitable source of power. On each rotation of the crank, the frame 34 descends to bring the rotating cutting knife into engagement with a protruding portion of the paraffin coated cork rod to slice a disk therefrom and then rises to permit the protrusion of a fresh portion of the rod for the next cut.

On each rising movement, the frame 34 swings the rocker arm 48 whereby to thrust the arm 49 downwardly and to cause the pawl 50 to advance the ratchet wheel 51 100 the distance of one tooth. The rocker arm 48 is carried by a pivot stud 52 projecting from the horizontal portion 13, and the pawl 50 is pivoted at 53 to the arm 49 and yieldingly held to the ratchet wheel by a spring 105 54 pinned to said arm 49 at 55. Said arm 49 is loosely mounted upon a short shaft 56, rotatably supported in bearing-lugs 57 formed on the tubular guide. A pull spring 58 which connects the arm 49 with the horizontal portion 13, serves to keep the rounded end 59 of said arm in contact with the rocker arm forcing the latter into position for the next swing as it follows the downward movement of the frame 34. The 110 ratchet wheel 51 is fast on the shaft 56, which also carries a relatively small toothed wheel 60 that operates through an opening 61 in the tubular guide to bite into and advance the paraffin coated cork rod a short 115 distance each time the ratchet wheel is actuated.

The bore 19 of the tubular guide is preferably made somewhat larger than the diameter of the paraffin coated cork rod and 125 the latter is operatively held in the teeth of the wheel 60 by a roller 62 which operates through an opening 63 cut in the tubular guide and which is supported upon a yieldable angular frame 64 having its rear end 130

pivoted at 65 to the tubular guide and its front end mounted upon a spring wire 66 depending from said tubular guide. A wing nut 67 threaded upon the spring wire serves 5 to adjust the position of the forward end of the bracket whereby to tighten or loosen at will the pressure exerted by the roller upon the cork rod. The roller 62 is engaged on a pintle 68 rotatably mounted in the arms 69 10 formed with the bracket 64. By means of this construction the cork rod is automatically advanced through the tubular guide a distance equal to the thickness of the disk-shaped piece to be cut therefrom each time 15 the cutting knife is elevated. A funnel-shaped receptacle 70 is preferably fitted in the base 10 to receive the disk-shaped pieces as they are sliced from the cork rod by the cutting knife.

20 Having thus described my invention what

I claim as new and want to protect by Letters Patent is:—

1. The process of cutting rods of cork or other suitable materials into comparatively thin disks, which consists in first applying 25 a thin coat of paraffin, ceresin or similar oily, fatty or waxy materials to said rods and then passing said rods through suitable devices for the cutting of said disks.

2. The process of preparing disks for 30 crown corks, which consists in dipping a rod of cork into molten paraffin, ceresin or similar oily, fatty or waxy materials, cooling the coating of said rod and passing said rod, thus coated, through the usual devices 35 for cutting the cork disks.

In testimony whereof, I have signed my name to this specification this 12th day of January, 1923.

RALPH W. BOOTH.
